HYDROFOIL BOAT

John Bader, Montgomery County, Md.
(4513 Sangamore Road (Apt. 101), Washington, D.C.)
Filed July 30, 1964, Ser. No. 386,466
15 Claims. (Cl. 114—66.5)
(Granted under Title 35, U.S. Code (1952), sec. 266)

The invention described herein may be manufactured and used by or for the Government of the United States of America for governmental purposes without the payment of any royalties thereon or therefor.

This invention relates to hydrofoil craft and more particularly, to improved hydrofoil retraction means by which symmetrically mounted primary lifting foils supporting most of the craft may be extended to a locked surface-piercing position of rigid support and by which the foil may be retracted to a compact stowed position located alongside the hull in a dry position essentially above the craft's displacement waterline. A feature of the hydrofoil craft of the present invention is a novel hydrofoil mounting arrangement for the outboard unit of an "inboard-outboard" power plant employed on the improved craft.

In overcoming the difficulties basic to hydrofoil craft of rigidity of support and of facility of retraction to a dry position without detracting from stability, the novel retraction means provides in its extended position a wide V-shaped hydrofoil support without reverse dihedral positions which would lessen stability. The retraction means itself is composed of a plurality of support members all of which are pivotable. When retracted, these members including the hydrofoils lie substantially flush against the hull. When extended, these pivotable members form a plurality of triangular frames which insure rigidity of the hydrofoil against lift forces and impact loads, and which locate opposing hydrofoils on either side of the craft so that the lift forces of the opposing hydrofoils converge to a point above the craft's center of gravity. Because all of the support members are pivotable, only a minimum of small brackets are required to be affixed to the hull to support the retraction means, consequently rendering the retraction means easily mountable on existing hulls without expensive and unsightly hull alterations.

In further carrying out the invention, in view of the wide present day acceptance of power plants of the "inboard-outboard" type, there is provided for such powerplant in the hydrofoil craft of the present invention a surface-piercing, V-shaped hydrofoil which is advantageously located on a lengthened surface-piercing propeller strut an appreciable distance above the propeller so that, unlike previous known designs, there is no possibility that the propeller can be lifted out of the water by the hydrofoil at flying speeds. Together with the foregoing advantageous arrangement there is further provided additional support means for strengthening the outboard unit of the powerplant to transmit to the hull the lift forces produced by the propeller strut hydrofoil. Since such lift forces are transmitted to the hull, the strut hydrofoil provides the additional advantage of stabilizing the hull attitude in its water-displacement made by lifting the stern to prevent "porpoising" or squatting.

It is, then, among the objects of the present invention to provide: an improved hydrofoil craft of the type employing "inboard-outboard" powerplants including improved primary retractable hydrofoil means and additional hydrofoil means for the support of the aft portion of the hull through the outboard unit of the powerplant; improved hydrofoil retraction means composed entirely of easily movable pivotable support members extendable to a rigid, locked position; an improved hydrofoil craft having a unique arrangement of pivotally mounted sup-

2

port members which can be separately fabricated and attached to a hull in a simple manner; an improved hydrofoil craft to the hull of which is attached a set of surface-piercing hydrofoils which can be retracted simply and easily into a compact, dry stowage position alongside the hull; an improved hydrofoil craft having a minimum number and size of hull appendages to which hydrofoil retraction means may be attached and by which the retraction means may be easily moved to an active extended position and to a passive, stowed position and from which the retraction means may, if desired, be easily removed; and, in a hydrofoil craft improved aft-supporting hydrofoil and mounting means for a powerplant of the type having an extended surface-piercing strut whereby the dynamic riding qualities of the craft are enhanced both in the flying and water displacing modes.

It is a feature of the present invention to provide novel means for strengthening the support of known types of "inboard-outboard" powerplants so that they may be fitted with hydrofoil means according to the invention. It is typical of the known types of "inboard-outboard" powerplants that the surface-piercing propeller struts are rotatable about a vertical axis for steering and about a horizontal axis for withdrawal or shock load yielding of the outboard unit of the powerplant. However, the usual design of these rotational axes is only sufficiently strong to resist the forward thrust of the propeller. In view of the fact that a hydrofoil positioned on the strut in accordance with the present invention produces a vertical lift force of about three times the thrust force of the propeller, it is necessary to provide in accordance with the invention additional clamping and load transfer members arranged in a novel manner to compensate for the additional hydrofoil lift without disturbing the rotational axes of the powerplants as designed.

A better understanding of the above and other features of the present invention will be obtained by reference to the following detailed description and accompanying drawings throughout which like numerals represent like parts and in which:

FIG. 1 is a modified transverse cross sectional view of a hydrofoil craft according to the invention depicting the respectively the extended and retracted positions of the primary hydrofoil; and

FIGS. 2 and 3 are views in side elevation depicting respectively the extended and retracted positions of the primary hydrofoil;

FIGS. 4 and 5 taken together are respectively side elevation and end views also showing certain details in cross section, of the outboard unit of the powerplant according to the invention.

Referring to FIGS. 1-3 taken together, there is shown therein a boat 11 having a V bottom 13 extending from a keel 15 and joined to a side 17 at a chine 19. The side 17 is joined to the deck 21 at a gunwale 23. The hydrofoil retraction means for a hydrofoil on either side of the craft will now be described as oriented in its extended position shown in solid lines in FIG. 1 and in FIG. 3.

A pair of brackets 25 supporting a hinge 27 are located forward of the boat's center of gravity adjacent the gunwale 23 on the side 17. The hinge 27 is oriented approximately parallel to the gunwale. The hinge 27 supports the upper end of an upper link 29. The lower end of the upper link carries a transverse hinge 31 of any suitable construction to which is attached the upper end of a strut 33 so that the strut swings freely about the hinge 31 in a transverse plane.

The lower end of the strut 33 has a hinge 35 to which is attached the corner portion of a dihedral type hydrofoil 39. The hydrofoil 39 has an inwardly projecting foil portion 41 which is oriented to ride in a plane approximately parallel to the water surface, and an outwardly

extending, surface-piercing foil portion 43 which as best seen in FIG. 3 is swept back as it extends outwardly.

Near the sweptback extremity of the foil portion 43, which rides above the water surface, is a bracket mounted hinge 45 to which is attached the outer end of a brace 47. The inner end of the brace 47 is attached to a bracket mounted hinge 49 located in the same transverse plane as the hinge 45 and mounted along the chine 19. The brace 47 may be further held against fore and aft movement by a strut 51 swivelly attached at its forward end to the aft portion of the brace and attached at its after end to the hinge 49 for rotation therewith. This added fore and aft support may be desirable where considerable forces are expected, such as, in very high speed operation. If desired, the brace 47 may be swept forward.

The strut 33 is provided with transverse support by a lower link 53 the upper end of which is attached to a bracket-mounted hinge 55 extending along and adjacent to the chine 19, and hingeably attached at its lower end to the hinge 57 located on the lower central portion of the strut 33. The lower link 53, upper portion of the strut 33 and the side 17 together form a triangular or A frame element for supporting the hydrofoil in the transverse plane.

In order to hold the strut 33 in place against transverse movement caused primarily by hydrofoil lift forces during turns, there is provided a clamp 59 mounted on the side 17 a short distance below the gunwale 23. The clamp 59 is composed of a pair of brackets for holding a rod 61 against the outer surface of the upper link 29 so that the upper link is held in place preventing movement of the strut 33 and lower link 53 in a transverse plane.

If desired, additional fore and aft support for the strut 33 is provided by a support member 63; shown in FIGS. 2 and 3, one end of which is rotatably mounted on the hinge 55 aft of lower link 53 and the other end of which is swivelly attached to the lower link 53. Of course, all of the hinges are parallel to each other.

The retractable hydrofoil means just described may be retracted by any suitable means, such as by hand, power operated means of known construction, and remote control power means. The act of retracting the hydrofoil and the accompanying movements of the retraction apparatus will now be described with particular reference to FIG. 1. First, the rod 61 in the clamp 59 is removed. The upper link 29 is then rotated about hinge 25. When the lower end of the upper link 29 has reached position "A," the lower end of the strut 33 has been moved slightly downwardly and inwardly to its "A" position due to a small relative pivoting motion of the strut 33 about the hinge 57 at the lower end of the lower link 53 as link 53 is pulled outward by the strut to its "A" position. Consequently the hinge 45 at the extremity of the brace 47 drops slightly to its position "A," and the hydrofoil 39 has moved slightly inwardly to its "A" position with strut 33.

As the upper link 29 is rotated further to its "B" position, which can be observed to be higher than its "A" position, the strut 33 is pulled upward, its upper end rotating about hinge 31 and its lower end arriving at position "B"—almost directly above the original extended position of hinge 37. The hydrofoil 39 has also reached its position "B" which is just above its original position.

Before proceeding further, it is noted that the initial reverse movement of the hydrofoil 39 and associated linkage to position "A" provides an additional locking bias against outward forces when the hydrofoil is fully extended. This locking bias further inhibits collapse of the retraction system on sharp turns where outward acting forces are at a maximum on either the starboard or port side of the boat.

Continuing with the retraction, upper link 29 is further rotated about hinge 25 so that its extremity at hinge 31 reaches position "C." Hinge 35 at the bottom of the strut 33 therefore travels generally upwardly to its position "C,"

pulling along with it the hydrofoil 39 and the brace 47. Thus, while the strut 33 is generally moved in translation, the brace 47 is rotating about fixed hinge 49 along with its support 51 and the hydrofoil 39 is moving in both translation and rotation so that the hinge 45, brace 47 and the hydrofoil 39 has reached its "C" position.

The upper link 29 is rotated so that the hinge 31 comes to rest at the position of full retraction, "D." As best shown in FIG. 3, in the retracted position the upper link 29 protrudes for approximately its own length above the deck 21; the strut 33 has been moved primarily in translation so that it is drawn flush against the side 17 with its upper end protruding above decks coextensively with the upper link 29. The brace 47 has been rotated about hinge 49 so that it rests flush against the side 17. The hydrofoil 39 has been moved primarily in translation so that it overlies the strut 33 and the top of brace 47 adjacent the side 17 in a swept back fashion with its inner foil element 41 resting adjacent the V bottom 13. The lower link 53 has been rotated about the hinge 55 so that it rests against the side 17.

The hydrofoil may be locked in its retracted position by any suitable means which, by way of illustration only, may be a clamp located on the side 17 or by deck hardware of known construction. Of course, the hydrofoil may be lowered in a reverse manner to its retraction described above.

By way of illustration and not limitation, the various linkages in the primary hydrofoil retraction means may have the exemplary relative dimensions shown in the following table, assuming the transverse length of the side 17 to have a length $2r$:

Part	Preferred dimension	Approximate ranges of dimensions
Lower link 53	r	r .
Upper link 29	r	About r or slightly less.
Strut 33	$2.8r$	About $2r$ to $3.5r$.
Brace 47	$2.2r$	About $2r$ or greater.
Foil portion 43	$2.65r$	About $2\frac{1}{2}r$.
Foil portion 41		About optional $\frac{1}{2}r$ recommended.

Reference is now made to FIGS. 4 and 5 in which is shown an "inboard-outboard" powerplant modified in accordance with the invention to carry a hydrofoil to provide, along with the primary foil 39, an improved hydrofoil craft.

More particularly, there is shown in FIGS. 4 and 5 components of a conventional "inboard-outboard" powerplant which includes a drive shaft 71 with its tubular housing 73 extending thru the boat's transom 75. The drive shaft 71 extends thru an outboard connect fitting usually in the form of a hollowed out casting 77 to an upper gear box 79 which generally has co-acting bevel gears to transfer the drive shaft rotation to an intermediate drive shaft (not shown) extending thru a hollow faired strut section 81 to a lower gear box 83. The housing 73 has at its aft end a flange 84 located externally of the transom.

The lower gear box 83 has beveled gears which coact to transfer the rotation of the intermediate drive shaft to an output shaft 85 carrying a propeller.

Furthermore, the conventional "inboard-outboard" unit has a horizontal or transverse pivot with its axis 86 extending thru the casting 77 so that the lower part of the unit may be lifted from the water, or may yield due to shock loading on the lower part of the unit. A shear pin is usually provided in the lower part of the casting 77 to hold the unit in place when underway. Of course, the drive shaft may be provided with a universal joint (not shown) with an axis coaxial with the horizontal pivot axis 86. The gear box 79 is generally in the form of a casting having a shaft housing 87 terminating in a flange 89 at its lower end. The flange 89 is bolted

to a flange 90 of like dimension located at the uppermost end of the hollow strut 81.

The housing 87 has at its forward portion and integral therewith an upper pad 91 having an aperture 93 and a pad 95 located below and spaced from the pad 91 having an aperture 97 coaxial with aperture 93. A pivot pin 99 is positioned in the apertures 93 and 97 and in corresponding apertures located in the flanges 90, 91, so that the outboard portion of the unit may rotate about the pivot pin for steering the boat.

The forward part of the casting 77 also has a tubular extension 100 which fits inside the housing 73 to hold the outboard unit in place.

In carrying out the present invention, the hollow, faired strut 81 is lengthened. A V-shaped, surface-piercing hydrofoil 101 which may be either in line with or swept back from, the transverse plane of the strut 81 is mounted on the strut an appreciable distance above the axis of the propeller shaft 85. The location of the hydrofoil above the propeller shaft is significant because, contrary to prior arrangements, such a location insures that the hydrofoil will not be able to lift the propeller out of the water. Of course, the use of a swept back hydrofoil has the advantage of reducing shock loading on the hydrofoil and its supporting elements.

As indicated in FIG. 4 by the three arrows X, Y and Z emanating from origin O, the hydrofoil 101 produces a drag component X and a lift component Y which together produce a resultant force Z which tends to cause via the lever arm action of the strut 81 great strain on the tubular extension 100 and also places considerable strain on the casting 77 against shear pins usually provided to hold it in place. This resultant force Z may be of a value about three or more times as great as the thrust of the propeller.

According to the invention the outboard unit is strengthened to accept the hydrofoil-produced forces first by inserting an annular bearing plate 103 of sturdy construction within the cupped flange 84. The portion of the casting 77 adjacent the ring 103 is strengthened by fin-shaped weldments or integral webs 105 which welded or securely fastened in any suitable manner to the annular bearing plate 103.

An inverted "A frame" 107 of sturdy construction is inserted within the open end of the casting 77 so that its lower crossmember 108 is secured to the pad 95. The upper and lower cross members 108a and 108 respectively, of the "A frame" 107 are apertured to receive the pivot pin 99. The bottom of the casting 77, the pad 95 and the lower end of the "A frame" are provided on both sides with lateral apertures 109 for receiving shear pins 111. The upper end of the "A frame" 107 is secured by any suitable means to the pivot at horizontal axis 85. Thus, the "A frame" via the shear pins 111 and its upper mounting at axis 85 takes up some of the forces which would otherwise be transmitted to the transom solely via the casting 77 and thus serves to reinforce the casting 77.

In order to provide for transmission of forces to the "A frame" and thence to the transom, a pair of canted braces 113 located on either side of the casting 77 are at their lower ends welded to the flange 89 and at their uppermost ends to the upper pad 91.

Therefore, responsive to the Z forces tending to rotate the strut and outboard unit about the plate 84 (because the pivot at axis 85 is located by shear pins 111), such forces are transmitted principally via the strut flange 90, flange 89, braces 113, "A frame" 107 and pin 97, webs or weldments 84 to the annular bearing plate 103, thus alleviating the conventional outboard unit from strains which would otherwise be subjected to the hydrofoil-produced forces.

The attitude of the hydrofoil 101 and the attack angle of the propeller may be adjusted by changing the location of the shear pins 111 in apertures 109. As a guideline, 75

but not by way of limitation, the primary hydrofoil 39 may provide about 75% of the lift while the aft hydrofoil 101 provides the remaining 25% of the lift.

The aft V-shaped hydrofoil 101 not only provides lift in the flying mode of the craft, but further provides a rudder effect to facilitate steering. There is also provided a stabilizing effect to minimize "porpoising" in the water-displacing mode because the hydrofoil 101 will tend to cause the stern to move up and the bow to move down.

It is appreciated that due to the fact that the various elements of the primary hydrofoil retraction means is composed of hinged parts, it may be easily fabricated and supplied to users in easily assembled kit form. Of course, the sizes and proportions of the various elements depend upon the size and displacement of the craft to be supported thereby, and the elements may be supplied to users in sets appropriate to the dimensions and displacement of the craft. Obviously, any suitable materials may be used for the elements, such as, for example, structural metals and alloys thereof, plastics such as fiberglass or the like, and wood. It is appreciated that especially where metals are used, the fact that according to the invention the hydrofoil unit retracts to an essentially dry position inhibits corrosion, erosion and deterioration of the hydrofoil material.

Obviously many modifications and variations of the present invention are possible in the light of the above teachings. It is therefore to be understood that within the scope of the appended claims the invention may be practiced otherwise than as specifically described.

What is claimed is:

1. An improved hydrofoil craft having sides and a bottom, said craft having surface piercing strut means supporting propeller means, comprising:

at least one primary hydrofoil unit having separate hydrofoil elements located symmetrically about and displaced transversely outward of the centerline of the craft, said hydrofoil unit being mounted forwardly on the craft;
retraction means for said hydrofoil elements;
said retraction means comprising a plurality of support elements hingeably mounted on the external sides of the craft and connected to the hydrofoil element;
said support elements when extended forming with the side a plurality of rigid triangular braces connecting the hydrofoil element to the sides;
said support elements being collapsible by relative rotation thereof about the respective hinged interconnections to raised positions essentially flush alongside the sides of the craft and essentially above the displacement water line of the hull;
a secondary hydrofoil unit including foil means mounted on the propeller strut means an appreciable distance above the propeller means.

2. Apparatus according to claim 1 wherein the secondary hydrofoil unit comprises surface-piercing V-shaped hydrofoil means.

3. Apparatus according to claim 2 wherein said plurality of support elements comprises:

upper and lower spaced links each mounted on the side of the hull for rotation about one end in essentially one transverse plane;
a strut supported by the other end of both said links, the upper end of said strut being pivotally connected to the other end of the upper link and the strut pivotally connected in its central portion to the other end of the lower link;
means pivotally connecting the lower end of said strut to an inboard portion of the hydrofoil element, and a brace mounted to the hull at its inner end and at its other end to the outer end portion of the hydrofoil element; and
means locking said upper link in a downward extending position alongside the hull, whereby the hydro-

foil element is locked in an operating position by said lower link, strut and brace, said upper link when rotated to a raised position causing movement of the lower link, strut, hydrofoil and brace to a raised position alongside the hull.

4. Apparatus according to claim 3 including additional support means for said brace and for said lower link for further locking the hydrofoil elements against fore and aft movement.

5. Apparatus according to claim 3 wherein the retraction means is characterized by the ratio of the length of the lower link to the strut upper link, brace and hydrofoil being of respective values such that during a large portion of the extension of the retraction means the hydrofoil moves in rotation and translation in a first directional sense and in a second essentially opposite directional sense for a small distance of extension into its locked down position.

6. Apparatus according to claim 5 wherein said ratios are characterized by the following respective values, said lower link having a length r ; lower link to strut, r to approximately $2.8r$; lower link to brace, r to approximately $2.2r$; lower link to hydrofoil, r to approximately $2.6r$, and lower link to upper link, r to approximately r .

7. Apparatus according to claim 6 wherein the length of the side of the craft in transverse cross section at the approximate plane of retraction is at least $2r$.

8. Retraction means for each surface-piercing, swept back hydrofoil of a water craft having sides and a bottom, and supported by a symmetrical array of hydrofoils, each hydrofoil being mounted as a separate unit on one side of the craft, comprising:

upper and lower links;

means rotatably mounting the one end of the upper link at the upper portion of the side and one end of the lower link directly below the upper link approximately at the junction of the side and bottom;

said upper and lower links being of dimensions so that their other ends may rotate in the same transverse plane of the watercraft free of each other;

a strut rotatably attached at its upper end to the other end of the upper link and rotatably attached in the vicinity of its central portion to the other end of the lower link;

said strut being of a length at least greater than the combined length of said links;

means rotatably attaching the submersible portion of the surface-piercing hydrofoil element to the lower end of said strut;

a brace rotatably attached at one end to a lower portion of the side of the craft and at its other end to the swept back above-surface portion of the hydrofoil;

the hull attachment point of said brace being located in a place different from said transverse plane; and means for holding the upper link in position against the side whereby the retraction means is held in an extended position, the hydrofoil thereby being held in a rigid surface-piercing position by virtue of transverse frames constituting in one instance a portion of the side, said lower link and said strut and in another instance said brace, hydrofoil and strut, and in another plane, constituting said brace, hydrofoil and a fore and aft distance along the side;

said retraction means when drawn up lying essentially flush alongside and above the water displacement line of the water craft.

9. Retraction means according to claim 8 but further characterized by additional fore and aft support means rotatably attached to said lower link and to said brace.

10. Retraction means according to claim 9 wherein each of said links has a length r , the length of the brace is approximately $2.2r$, the length of the strut is approximately $2.8r$ and the length of the hydrofoil is approximately $2.6r$;

said lower link being connected to said strut at a

location approximately a distance r above the connection point of the strut to the hydrofoil, whereby during most of the extension of the retraction means the hydrofoil moves in rotation and translation in a first directional sense and during its final brief movement into full extension moves in a directional sense essentially opposite to said first directional sense thereby establishing a locking bias for the hydrofoil.

11. Retraction means for each one of a plurality of surface-piercing hydrofoils symmetrically arranged on a watercraft having sides and a bottom, comprising:

a first plurality of support members each rotatably attached at one end to respectively different portions on the side;

a second plurality of support members each rotatably attached at one end to different portions of the hydrofoil;

means rotatably connecting the other end of one of said second plurality of support members to the other end of one of said first plurality of support members; means rotatably connecting an intermediate portion of said one of said second plurality of support members to the other end of another of said first plurality of support members, and means rotatably connecting one of said first plurality of support members to an above-surface portion of the hydrofoil whereby the hydrofoil is extendable to a position supported by triangular elements formed by said support members and is retractable to an alongside position in which said support members are overlyingly collapsed.

12. Retraction apparatus for a hydrofoil craft having sides and a bottom and having hydrofoil elements mounted as single units on both sides of the craft symmetrically about the craft's centerline axis, the retraction apparatus for each hydrofoil element comprising:

an upper link rotatably mounted at one end at the approximate top of the side and a lower link having one end rotatably mounted at the approximate bottom of the side;

each of said links being rotatably in essentially the same transverse plane and in paths free of each other; a strut at least longer than the combined length of said links and rotatably attached at its uppermost end to the other end of said upper link and rotatably attached at a point approximately near its lower end to the other end of said lower link;

said strut being rotatably attached at its lowermost end to the inboard portion of the hydrofoil element; a brace rotatably attached at one end to the side for rotation about an axis which is at least approximately coaxial with the rotational axis of said lower link; the other end of said brace being rotatably attached to a point near the outer end of the hydrofoil element; the length of the brace being less than that of said strut whereby when the unit is extended, the hydrofoil element is located in a surface-piercing attitude; said hydrofoil element being of a length at its points of connection to the strut and brace at least greater than the length of the brace;

whereby in the extended position essentially rigid hydrofoil element-supporting triangular elements are formed by the lower link, craft side and strut and further by the brace, hydrofoil and longitudinal portion of the side;

and further, whereby upon retraction said strut and hydrofoil are both rotated and translated due to relative rotation of the links about the rotatable attachments on said strut and due to relative rotation of the strut and brace about their respective and rotatable attachment points on the hydrofoil element; thereby raising all of the members to positions overlying each other with the foil outermost essentially alongside the side coextending to the juncture of the side and bottom.

13. Apparatus according to claim 12 wherein said hy-

drofoil element is swept back from submergible inboard portion toward its above-water aftward portion, the point of rotation of said brace being aft of the rotational axis of said lower link.

14. Apparatus according to claim 13 but further including clamp means attachable to the side for holding the upper link in a down position alongside the side, whereby the unit when extended is further locked in a position wherein the members form triangular support elements. 5

15. An improved hydrofoil craft having sides and a bottom, said craft having a propulsion unit including an inboard powerplant and an outboard drive unit extending from the powerplant thru the craft's transom, said outboard drive unit having a drive shaft housed in a surface-piercing strut extending downward to a propeller shaft, and wherein the outboard unit is of the type supported essentially by a sleeve bearing against a tube passing thru the craft's transom, said tube having an exterior cupped flange portion, said outboard unit having an aftward-opening shell-like fitting for holding horizontal axis pivot means for said outboard unit, said fitting being integral with the sleeve, and a gear box housing with upper and lower spaced pads extending into the fitting for holding a steering pin, and further, said gear box terminating at its lower end in a flange and the surface-piercing strut terminating at its upper end in a flange abutting said gear box flange, said craft comprising: 10

retractable hydrofoil means located essentially forwardly of the craft for carrying a primary portion of the craft's weight when the craft is flying;

20
25
30
35

aft hydrofoil means located on the surface-piercing strut for producing lift for the after portion craft in both its water displacing and flying modes; said surface-piercing hydrofoil being located at least appreciably above the axis of propeller rotation; and

means additionally supporting the outboard unit against the lift forces produced by said aft hydrofoil means, said means comprising:

an inverted A frame member resting on the lower pad of said gear box housing with its cross member supported by the upper pad and its ends supported by the horizontal axis pivot means; a pair of forwardly and upwardly canted braces connecting the gear box flange with the upper pad; and a bearing support ring located in said cupped flange and welded to the forward portion of the shell-like fitting, said shell-like fitting being held against the gear box housing by shear pin means acting via said inverted A frame;

whereby the resultant of the lift and drag forces acting on said outboard unit are transmitted via said braces and A frame stiffened fitting for strain reaction on said bearing support ring.
